ELECTRIC SPOTTING BRUSH FOR DRYCLEANERS

John Jedora, 33 Cedar N., Timmins, Ontario, Canada

Filed Feb. 20, 1970, Ser. No. 21,539

Term of patent 14 years

Int. Cl. D4—02

U.S. Cl. D4—14

FIG. 1 is a front view of the electric spotting brush for drycleaners with an associated electric driving mechanism shown in broken lines for illustrative purposes only;

FIG. 2 is a side view of the brush of FIG. 1 as seen from the left of FIG. 1;

FIG. 3 is a side view of the brush of FIG. 1 as seen from the right of FIG. 1; and

FIG. 4 is a top view of the brush of FIGS. 1, 2 and 3.
I claim:

The ornamental design for an electric spotting brush for drycleaners, as shown and described.
